UNITED STATES PATENT OFFICE.

CHRIS BORG, OF CHICAGO, ILLINOIS, ASSIGNOR TO INTERNATIONAL HARVESTER COMPANY, A CORPORATION OF NEW JERSEY.

PNEUMATIC SPOKE-RIVETER.

SPECIFICATION forming part of Letters Patent No. 792,390, dated June 13, 1905.

Application filed December 21, 1904. Serial No. 237,738.

To all whom it may concern:

Be it known that I, CHRIS BORG, a citizen of the United States, residing at Chicago, in the county of Cook and State of Illinois, have 5 invented a new and useful Improvement in Pneumatic Spoke-Riveters, of which the following is a complete specification.

This invention relates to riveting devices, and is designed with special reference for use 10 in connection with the manufacture of large-sized metal wheels. In its application, as herein shown, it is used for securing the spoke of the wheel to the hub thereof.

The object of the invention is to provide a 15 simple and compact riveting device in which both the heading-tool and gripping-jaws will be actuated by single means. To accomplish this, a novel construction and arrangement of parts is devised whereby continued 20 movement of the heading-tool will be permitted after the gripping-jaws have reached their closed or gripped position.

The preferred form of this invention is disclosed in the accompanying drawings, in 25 which—

Figure 1 is a side elevation of the complete device, and Fig. 2 is a corresponding side view with a portion of the frame cut away. Fig. 3 is an elevation of the left-hand side as 30 viewed in Fig. 1. Fig. 4 is a horizontal longitudinal section of the spoke-riveter, taken as indicated by the line 4-4 in Fig. 2. Fig. 5 represents a horizontal longitudinal section taken as indicated by the line 5-5 in Fig. 2 35 and is designed to show the pivotal axes of the gripping-jaws and heading-tool, while Fig. 6 is a detail section taken longitudinally of the pivotal axis of the piston-rod with the double link of the toggle connection between 40 the heading-tool and riveter-frame. Fig. 6^a represents a fragmentary plan view of the toggle connection between the upper ends of the levers of the spoke-gripping jaws. Figs. 7 and 8 are diagrammatic views illustrating 45 the relative position of the heading-tool and the links which actuate the heading-tool and gripping-jaws in the various stages of their movement, Fig. 7 showing in full lines the initial position of the several parts before

movement thereof has begun, while the two 50 series of dotted lines in this figure show successive positions of the parts, and Fig. 8 showing in full lines the relative position of parts after having completed its downward movement. The first dotted-line position 55 corresponds with the last or third position shown in Fig. 7, while the second dotted-line position in this figure shows the position of the parts after the gripping movement of the jaws has been completed. This figure is de- 60 signed to illustrate the manner in which the gripping-jaws are permitted to remain practically stationary, while the heading-tool continues in its movement.

In the drawings, 1 designates the frame of 65 the machine, the frame consisting in the main of a rectangular-shaped casting with a centrally-located vertically-extending slot 2 formed therein. On the sides of this slot are formed the rearward-projecting ribs, the 70 lower margins of which are connected by the strengthening-web 4. On the lower end of the frame 1 is pivotally mounted the two spoke-gripping jaws 5, the pivotal bearing of said jaws being formed by the eyebolts 6. 75 The eyes of these bolts 6 receive the pin 7, which forms the pivotal bearing of the upsetting-tool 8, thus resulting in a construction which brings the axes of the spoke-gripping jaws 5 and the axis of said heading-tool in a 80 common plane.

To the upper end of the heading-tool 8 and on either side thereof is pivotally connected the double arms 9, (see Fig. 4,) the pivotal bearing being formed by the pin 10. Move- 85 ment is imparted to the mechanism by means of the piston-rod 11, which connects with the rear end of said double arms 9. Intermediate of the length of these double arms and lying therebetween is pivotally connected on 90 the pin 12 the link 13, the rear end of which is pivotally mounted on the frame 1 by means of the pin 14. The said link 13 and the double arms 9 thus form a toggle connection between a fixed part of the frame of the ma- 95 chine and the upper end of the heading-tool 8, while that portion of the double links which extends rearward beyond the pivotal

connection formed by the pin 12 may be regarded as an extension thereof, with which the operating means articulates.

- The spoke-gripping jaws are actuated in the following manner: Double links 15 15 (see Fig. 3) form a toggle connection between the upper ends of the spoke-gripping jaws 5, the pins 15' forming the bearing between the said jaws and links, while the pin 16 forms the bearing between the two double links. Journalled on the pin 16 between the said links 15 is the block 17, having the two transversely-extending eyes 17' on the lower end thereof, between which eyes journals the link 18. To the lower end of the link 18 is pivotally secured the triangular-shaped plate 19, the links 21 and 22 connecting the base of said plate respectively with the heading-tool 8, near the upper end thereof, and with the pin 12 in the toggle connection between said heading-tool and frame of the riveter. The relative lengths of the several links and the relative location of the pivotal axes thereof are such that single means are employed to actuate both the spoke-gripping jaws and heading-tool, and continued movement of the heading-tool is permitted after the gripping movement of the jaws has ceased, as will hereinafter be more fully explained.
- To insure uniform movement being imparted to both of the spoke-gripping jaws 5, the rear end of the pin 16 is provided with a flattened end 16', arranged to slide in the longitudinally-extending groove or way 20, formed in the upper front side of the main frame, and thereby guide the toggle-joint.
- To operate the heading-tool and spoke-gripping jaws, a cylinder 23, provided with suitable flanges 23', is bolted to the upper end of the main frame 1 by means of the bolts 24. Within this cylinder 23 is fitted a piston 25, which pivotally connects with the upper end of the piston-rod 11. The piston is provided with a long guide 25', since the piston-rod itself does not operate as a guide for same. This guide is shown projecting from the lower end of the cylinder in Fig. 2. The valve 26 admits pressure to the cylinder, and this valve is operated through the link 27, which pivots to the cylinder at 28. This valve mechanism and lever for operating same is not shown in detail, as it is not material to the invention. Any suitable form of cylinder and mechanism for controlling the air or other medium thereto would do equally as well. A stay-rod 29 extends from the rear side of the cylinder to the lug 4', which is formed on the upper end of the web 4 of the main frame 1.
- Air-pressure is preferably used, and in operation the mechanism is suspended above the wheel operated upon by means of a cable or chain, (not shown in the drawings,) the cable or chain being attached to the bar 30, which has the eye 30' formed in the upper end there-

of. On the rear end of the arms 9 are formed the inwardly-projecting lugs 9', sufficient space being left therebetween to receive the link 13. 31 designates the yoke, (see Fig. 6,) which engages said lugs and receives in a threaded aperture at the upper end thereof the piston-rod 11. This construction permits the double arms 9 to descend to a position parallel with the link 13, which amounts to a dead-center of this toggle connection. 75

The peculiar action due to the special arrangement of the pivotal centers of the links and the relative lengths of the links is set forth in Figs. 7 and 8. Referring to these figures, A b represents the link 13, A being the fixed pivotal axis thereof, while c B d represents the heading-tool with its fixed pivotal axis at B. a b c represent the double arms 9, pivotally connected at the point b with the link 13. For clearness the gripping-jaws are not shown; but the links 15, forming the toggle connection which operates them, is represented by the lines e j, while the link 18 is represented by the line e f and the triangular plate 19 by the triangle f g h, 90 these letters representing the pivotal connections thereof with the said links 18, 22, and 21, respectively. The pivotal connection of the link 21 with the heading-tool 8 is represented by i, so that the line g b will represent 95 the link 22 and the line h i the link 21. The full lines in Fig. 7 indicate the initial position of the various parts and the dotted-line position with letters having the exponent "2" represent the relative position of parts when 100 the movement of the gripping-jaws has practically ceased, while the dotted-line position shown by the letters having the exponent "1" represents a position intermediate of the positions just mentioned. An inspection of 105 this figure will reveal that in the extent of movement therein indicated the piston-rod 11 will have moved longitudinally an amount represented by the distance between the letters a and a², while the corresponding longitudinal movement of the link 18 is represented by the distance from e to e², being slightly above a line passing through j² j¹. This will cause the points j, which represent 110 the pivotal connection of the links 15 with the upper end of the gripping-jaws 5, to move from j to j² and in such movement effect the closing of said jaws. In that period of 115 the operation above noted the head d of the upsetting-tool has been made to approach its work the amount indicated, while the triangular plate 19 has been caused to move bodily and almost parallel in a downward direction. 120

Referring now to Fig. 8, it will be seen that 125 the last position of Fig. 7 corresponds with the first position in this figure, and the full lines in Fig. 8 indicate the final position or the position occupied by the several parts after the movement of both the gripping- 130

jaws and heading-tool has been completed. The letters having an exponent "2" indicate the first position shown in this figure and the last position of Fig. 7, as before stated, while the letters having an exponent "4" represent the final position of same. The letters having an exponent "3" represent the position occupied by the several parts when the point *e*, representing, as before stated, the axis of the pivotal connection between the link 18 and the toggle-links 15, is made to occupy a position on the line *j j* or on dead-center of the toggle-joint. It will be observed that the extent of movement between the first and second position in this figure is very slight and, furthermore, that the extent of movement between the second and third positions is very great, yet the gripping-jaws remain practically unaffected in both periods. In this connection attention is directed to the movement of the triangle *f² g² h²* in the first and second movements, respectively. In the first movement it will be seen that it moves downward bodily, when suddenly it begins to assume an upright position, with the point *f³* moving to the right to the position indicated by *f⁴*. This peculiar movement of the plate 19 will permit the point *e* to have a very slight movement on either side of its dead-center, which will impart practically no movement to the gripping-jaws and yet will not interfere with the continued movement of the heading-tool. To permit of this peculiar movement, the links 21 and 22, represented by the lines *h i* and *g b*, are of such a length that they will permit the point *f*, representing the axis of the pivotal connection between the link 18 and the triangular plate 19, to travel in a path corresponding very closely with the arc of a circle about the point *e* when on dead-center or on the line *j j*.

Having described the mechanism, its operation will be briefly given. A hub *x*, only a fragment of which appears, is placed in position upon a suitable support (not shown, since it is not essential to the disclosure of this invention) and fastened by suitable means. A spoke *w*, previously heated and having a shoulder *w'* formed thereon, is then placed within the die of the gripping-jaws 5, as shown in Fig. 1, the inner end of said spoke engaging the spoke-receiving aperture in said hub *x*. Air-pressure is then admitted to the cylinder 23 through the valve 26, which is operated by the lever 27. This will cause the piston to descend from the position shown in Fig. 1 to that shown in Fig. 2. The initial movement of the piston 25 effects movement of both the heading-tool and the spoke-gripping jaws; but when a position is reached in the descent of the piston in which the parts are brought to occupy a position corresponding with the first dotted-line position of Fig. 8, (this position being

designated by letters having an exponent "2,") movement of the gripping-jaws will 65 practically cease. The triangular plate 19 then swings to a substantially vertical position, as before described, permitting the jaws to remain stationary and allowing the heading-tool to continue in its movement until a head 70 is formed on the end of the spoke, as shown in Fig. 2. Pressure is then introduced on the opposite side of the piston, which will cause the parts to return to their normal position. The operation is repeated until all the spokes 75 have been secured to the wheel-hub.

Having thus described my invention, what I claim as new, and desire to secure by Letters Patent, is—

1. In a pneumatic spoke-riveter, in combination, a frame, spoke-gripping jaws and a heading-tool pivotally mounted thereon, a toggle connection between the said heading-tool and frame, a toggle connection between the said spoke-gripping-jaws, links connecting the toggle-links on the spoke-gripping jaws with the toggle-links between the heading-tool and frame and also with said heading-tool, and single means for actuating both the spoke-gripping jaws and heading-tool, substantially as described. 80

2. In a pneumatic spoke-riveter, in combination, a frame, spoke-gripping jaws and a heading-tool pivotally mounted on said frame, the pivotal axes thereof lying at right 95 angles to each other and in a common plane, a toggle connection between the said heading-tool and frame, a toggle connection between the said spoke-gripping jaws, links connecting the toggle-links on the spoke-gripping jaws with the toggle-links between the heading-tool and frame and also with the 100 said heading-tool, and single means for actuating both the spoke-gripping jaws and heading-tool, substantially as described. 105

3. In a pneumatic spoke-riveter, in combination, a frame, spoke-gripping jaws and a heading-tool pivotally mounted thereon, a toggle connection between the said heading-tool and frame, actuating means articulating therewith, a toggle connection between the said spoke-gripping jaws, a triangular plate, links connecting said plate with the said heading-tool and the pivotal axis of said toggle connection between the frame and heading-tool, and link connection interposed between said triangular plate and the axis of said toggle connection between the spoke-gripping jaws, substantially as described. 110 115

In testimony whereof I have signed my name to this specification in the presence of two subscribing witnesses.

CHRIS BORG.
